UNITED STATES PATENT OFFICE.

FRANK T. BROWN, OF DALE, INDIANA.

STAVE-CUTTING MACHINE.

SPECIFICATION forming part of Letters Patent No. 720,400, dated February 10, 1903.

Application filed June 2, 1902. Serial No. 109,975. (No model.)

To all whom it may concern:

Be it known that I, FRANK T. BROWN, a citizen of the United States, residing at Dale, in the county of Spencer and State of Indiana, 5 have invented new and useful Improvements in Stave-Cutting Machines, of which the following is a specification.

My invention relates to new and useful improvements in machines for cutting staves 10 for barrels, kegs, tanks, &c.; and its object is to provide means whereby the edge of a strip of wood may be quickly and accurately curved and beveled.

A further object is to employ a carriage 15 having novel means for feeding it toward and from the cutting mechanism.

Another object is to provide means for holding the stave securely in position during the cutting operation and automatically discharging the same thereafter.

Other objects are to provide means for adjusting the cutting device to produce the desired bevel upon the stave, to provide means for automatically throwing the carriage out 25 of operation when the cutting of each stave is completed, and to employ means whereby the carriage is driven in either direction from the shaft of the cutting device; and it consists in a construction and arrangement of 30 parts, as will be hereinafter described, and more particularly pointed out in the claims.

In the accompanying drawings, Figure 1 is a perspective view of the complete apparatus. Fig. 2 is a front elevation, the track being 35 broken away to show the carriage-operating drum and the automatic shifting mechanism. Fig. 3 is a plan view. Fig. 4 is a section on line 4 4, Fig. 3. Fig. 5 is a plan view of the carriage with the clamping mechanism removed and a portion of the ejecting mechanism broken away to show the draw-head. Fig. 6 is a section on line 6 6, Fig. 5. Fig. 7 is a rear elevation of the cutting mechanism. Fig. 8 is an elevation of the grooved pulley.

45 Referring to the drawings by numerals of reference, 1 is a rectangular frame having laterally-extending arms 2, which serve to support a track 3, extending across the front face of the frame adjacent to the top thereof. 50 Cross-strips 4 are arranged within the upper end of the frame 1, and a drive-shaft 5 is journaled thereon. This shaft is provided at the

forward end with a circular saw 6, and a small pulley 7, preferably formed of paper, is located at the opposite end of said shaft. 55 A suitable pulley 8 is arranged upon the shaft at a point intermediate its ends and is adapted to be driven in any suitable manner. Each of the cross-strips 4 is adjustably secured at their outer ends to the upright portions of frame 1. It will thus be seen that by adjusting them vertically the shaft 5 can be arranged at any desired incline.

A slot 9, as shown in Fig. 2, is formed at one side of frame 1 at a point below shaft 5 60 and serves as a guide for a shaft 10, extending through the frame and journaled at one end in one side of the track 3 and at the other end within a lever 11. This lever, as shown in Fig. 7, is pivoted to the rear end of the 70 frame 1 and is formed with slots 12 and 13, which are adapted to receive the shaft 10 and one end of an arm 14, respectively. This arm extends laterally from a rod 15, mounted in brackets 16 at the side of the frame. 75 An arm 17 is arranged at the forward end of said rod and is connected, by means of a link 18, with a lever 19, pivoted to the frame. The rod 15 is also provided with an arm 20, which curves upward between the rails of the track 80 3 and is provided at its end with a roller 21. A spring 22 is secured to a short arm 23, extending from the opposite side of the rod 15 and is connected to a guide-rod 24, mounted upon the frame 1 and serving to prevent lateral movement of the lever 19. 85 A pulley 25 is secured upon the rear end of shaft 10 and provided in one face with a groove 26. This groove is adapted to receive the small pulley 7, hereinbefore referred to, and is of sufficient width to permit a slight vertical movement of either shaft 10 or 5 before the pulley 7 will contact with either side of said groove. A drum 27 is secured upon shaft 10 at a point 90 between the rails of track 3, and cables 28 and 29 are secured thereto and adapted to be wound thereon in opposite directions.

A rail 30 is secured upon one side of the track 3 and is curved to conform with the edge of the stave to be cut. This rail serves 100 as a guide for grooved wheels 31 of a carriage 32. A tongue 33 extends forward from the carriage and is connected to the cable 28, hereinbefore referred to. Said tongue also

extends a desired distance to the rear of the carriage and is provided with a pulley 34, upon which is mounted the cable 29. The end of this cable is secured to a draw-head 35, 5 slidably mounted within the rear end of carriage 32 and held normally retracted by means of a spring 36. A beveled arm 37 is pivoted to the forward end of carriage 32 and is held at a desired incline by means of a 10 slotted link 38, adjustably secured to the forward end of the carriage in any suitable manner, as by means of a clamping-screw 39.

The carriage 32 is provided at one side with a solid top 40, which is slotted transversely, 15 as shown at 41, to receive sliding bars 42. These bars are pivoted to the outer ends of levers 43, fulcrumed at one side of the carriage and connected at their adjacent ends by means of links 44 with a fulcrum-bar 45, having 20 its outer end arranged to operate under the rear sliding bar 42, said fulcrum-bar being forced laterally by means of a spring 46, secured to the solid top 40 and to said fulcrum-bar. Rods 47 extend upward from the 25 top 40 and through a clamping-board 48, arranged upon said top. Springs 49 are arranged upon these rods and bear upon the board 48, serving to hold the same normally clamped upon the carriage-top. Levers 50 30 are pivoted to one edge of the clamping board or member 48, and the lower ends thereof are provided with cam-faces 51, which are adapted to bear upon the top of the carriage. The upper ends of the levers are connected by a 35 horizontal rod 52, which is also pivoted to a lever 53, fulcrumed upon the side of the clamping member 48 and extending to a point below the carriage 32. The end of the carriage serves to limit the movement of this lever in one direction and a headed rod 54 40 limits the movement thereof in the opposite direction, said rod being mounted in an aperture formed within the end of the carriage.

A trip 55, having a beveled upper face, is 45 arranged upon one of the arms 2 of frame 1 at a point slightly removed from a lug or stop 56, also arranged upon said arm. The trip 55 is adapted to operate lever 53 when the same is drawn thereover during the movement 50 of carriage 32, and the stop 56 serves to hold said lever in position after becoming released from the trip.

Suitable brace-rods 57 may be employed for 55 preventing lateral movement or sagging of the track in relation to the frame 1, and one or two of the curved rails 30 may be employed upon the track, as desired.

In operation the rail 30 is secured upon track 3 in such a manner that the curve there- 60 of will conform to the curve of the edge of the stave to be cut. The carriage 32 is drawn back upon the track a sufficient distance to permit the roller 21 and its arm 20 to be slightly depressed by the beveled arm 37, ex- 65 tending from the carriage. This will cause the rod 15 to partly revolve, thereby swing-

ing the lever 11 downward and carrying the shaft 10 and its pulley 25 therewith a sufficient distance to remove the sides of the groove 26 from contact with pulley 7. The 70 drive-shaft 5 can then be revolved without operating the shaft 10 and the carriage connected thereto. While the carriage is out of operation, as above described, a strip which is to be shaped into a stave is placed between the top 40 and the clamping member 48 and the sliding bars 42 are pressed laterally thereby. This will cause the spring 46 to become compressed. The operating-lever 19 is then 75 pressed downward, and this will cause the 80 rod 15 to swing its arm 14 downward and will bring the outer wall of groove 26 into contact with pulley 7. Shaft 10 will thus be revolved, and the drum 27 will operate the cables 28 and 29 thereon as the same are inverted in 85 their order of winding and unwinding. This will cause the carriage 32 to move forward upon the track, and at the beginning of such movement trip 55 will throw the upper end of lever 53 forward, thereby releasing the 90 board 48 and permitting the springs 49 to clamp the same upon the stave and hold the sliding bars 42 in position. The carriage will be guided forward upon the curved rail 30, and the strip held within the clamp will be 95 cut with the desired curved edge and said edge will be beveled according to the incline at which the circular saw 6 is held. When the carriage reaches the forward end of the track 3, the operating-lever 19 is released and 100 will be promptly raised by the spring 22, which at the same time will throw the roller 21 upward into the path of the beveled arm 37 and will raise the pulley 25, so as to bring the inner wall of its groove 26 into contact 105 with pulley 7. The revolution of shaft 10 will thus be promptly reversed and the drum 27 will operate the cables 28 and 29 thereon as the same are inverted in their order of winding and unwinding, thereby drawing the carriage back to its original position. Just prior to the completion of the return movement of the carriage 32 the lower end of the lever 53 is brought into contact with the beveled face of trip 55, causing said lever 110 to swing upon its fulcrum. The cams 51 will at the same time be pressed upon the top of the carriage and will raise the clamping member 48 and compress springs 49. As soon as the stave held between the clamp is released in this manner spring 46 expands and presses lever 45 outward, thereby causing rods 42 to slide within their guiding-grooves 115 41 and force the stave from the carriage automatically. The operation can then be repeated, as hereinbefore described.

In the foregoing description I have shown the preferred form of my invention; but I do not limit myself thereto, as I am aware that modifications may be made therein without 120 departing from the spirit or sacrificing any 130 of the advantages thereof, and I therefore re-

serve the right to make all such changes and alterations as fairly fall within the scope of my invention.

Having thus fully described the invention, 5 what is claimed as new is—

1. The combination with a carriage; of a clamping-board upon the carriage, means for holding said board normally pressed thereon, cams pivoted to the board and adapted to raise the same from the carriage, a lever for operating said cams, a trip for operating the lever, and a spring-controlled ejecting-bar mounted beneath the clamping-board.

2. The combination with a carriage, of sliding bars thereon, spring-operated levers for moving said bars transversely of the carriage, a clamping-board mounted upon the bars and adapted to prevent movement thereof, cams for raising said board from the bars, and a trip-operated lever for operating the cams.

3. The combination with a carriage, of sliding ejector-bars mounted upon said carriage, spring-operated levers connected to the bars and adapted to impart motion thereto, a clamping-board extending over said bars,

means for holding the board normally pressed upon the bars, cams pivoted to the board and adapted to raise the same from the bars, and a trip-operated lever for operating the cams.

4. The combination with a frame having a track thereon and a guide-rail upon the track, of a carriage thereon, a spring-controlled lever pivoted upon the carriage, laterally-movable ejector-bars mounted upon the carriage, link-and-lever connections between said ejectors and the spring-controlled lever, a spring-pressed clamping-board normally contacted with the carriage and adapted to prevent movement of the ejectors, cams pivoted to the clamping-boards and adapted to raise the same, a lever for operating said cams, and a trip for operating the lever at the commencement and completion of the movement of the carriage.

In testimony whereof I affix my signature 45 in presence of two witnesses.

FRANK T. BROWN.
